UNITED STATES PATENT OFFICE.

BRUCE K. INGLIS, OF MILWAUKEE, WISCONSIN, ASSIGNOR OF ONE-HALF TO CLEMENT W. INGLIS, OF MILWAUKEE, WISCONSIN.

OIL BURNER.

Application filed August 15, 1924. Serial No. 732,170.

This invention relates in general to improvements in the art of utilizing hydro-carbons for heating purposes, and relates more specifically to improvements in the construction and operation of automatically functioning oil burners especially adapted for use in connection with furnaces or boilers such as are ordinarily employed to heat buildings.

An object of the invention is to provide a hydro-carbon burner which is simple in construction and efficient in operation. Another object of the invention is to provide an extremely compact hydro-carbon or oil burner which is entirely automatic in operation and which may be readily installed in any standard furnace or boiler. A further object of the invention is to provide a hydro-carbon burner the continued operation of which is not dependent upon outside sources of energy such as electricity, water under pressure, or a municipal gas supply. Still another object of the invention is to provide an effective oil burner which is devoid of moving parts and which may be safely operated by relatively unskilled attendance. A further object of the invention is to provide simple and efficient controlling and regulating mechanism for oil burners and the like. These and other objects and advantages of the present improvement will be apparent in the course of the following description.

A clear conception of an embodiment of the invention and of the operation of devices constructed in accordance therewith, may be had by referring to the drawing accompanying and forming a part of this specification in which like reference characters designate the same or similar parts in the various views.

Fig. 1 is a relatively diagrammatic central vertical section through a fragment of a boiler having an improved hydro-carbon burner associated therewith.

Fig. 2 is a transverse horizontal section through the boiler and burner of Fig. 1, the section being taken along the irregular line II-II of Fig. 1, looking in the direction of the arrows.

The hot water boiler to which the improved hydro-carbon burner has been specifically applied herein by way of illustration rather than by way of limitation, is of relatively standard construction, comprising a lower or base section 27 forming an ash pit 41, and an upper or water jacket section 2 resting upon the base 27 and forming a combustion

chamber 3 which is disposed directly above the ash pit 41. The ash pit 41 is accessible upon removal of a front closure 21, and the combustion chamber 3 is likewise accessible through a fire door 30, the closure and fire door normally sealing the ash pit 41 and the combustion chamber 3 respectively, from the atmosphere. The top of the chamber 3 is spanned by a portion of the water jacket 2 which is ordinarily provided with a series of gas discharge openings 33.

The improved hydro-carbon burner comprises in general a central atomizing dome or bulb 4; an overflow oil basin 8 within which the atomizing bulb 4 rests; an annular inner wall 11 surrounding the lower portion of the atomizing bulb 4 directly above the overflow basin 8; an annular intermediate wall consisting of superimposed upwardly converging and diverging portions 13, 12 respectively which surround the annular wall 11 and the atomizing bulb 4; an annular outer wall 26 surrounding the intermediate wall; a lower casing 14 supporting the annular inner, intermediate and outer walls; a sheet metal air supply duct 15 connecting the lower casing 14 with the atmosphere; hydro-carbon or oil supply pipes 6, 16 connecting the interior of the atomizing bulb 4 with a supply tank 25; and air and oil controlling and regulating mechanism.

The atomizing dome or bulb 4 is provided with longitudinally extending external fins or projections 10 along the upper outer portion thereof, and may have a spreader plate 34 of relatively large diameter detachably secured to the upper extremity thereof. The upper inner portion of the atomizing bulb 4 is preferably provided with an annular trough or basin 7 having therein diametrically opposite notches or recesses adapted to engage the outer ends of a nozzle 5. The nozzle 5 is secured to the upper extremity of the oil supply pipe 6 the lower end of which has screw thread coaction with the basin 8 in order to secure the bulb 4 in place. The lower portion of the atomizing bulb 4 is provided with a series of gas discharge slots or openings 9 located directly above the basin 8 and just above the lower extremity of the annular inner wall 11. An overflow pipe 17 connects the basin 8 at a point somewhat above the bottom thereof, with the overflow receptacle 22 which is suspended from the end of a lever 40, the lever 40 being adapted to operate an emer-

gency cut-off valve 23 as will be later explained.

The annular inner wall 11 is suspended from the constricted portion of the intermediate wall by means of several spaced projections, and surrounds the initial air and gas mixing chamber 20 which communicates directly with the openings 9 and with the interior of the lower casing 14. The converging 10 lower portion 13 of the intermediate wall rests directly upon the lower casing 14 and forms an annular air supply conduit 39 communicating with the casing 14 and surrounding the wall 11. The lower casing portion 13 has a 15 series of upwardly directed openings 32 therein for permitting free passage of air to the annular chamber 36 which surrounds the intermediate wall. The diverging upper portion 12 of the intermediate wall surrounds the 20 annular final mixing and initial combustion chamber 38 which is in open communication with the mixing chamber 20 and with the air supply conduit 39. The outer annular wall 26 is supported directly from the lower casing 25 14 and surrounds the air chamber 36 which communicates directly with the openings 32. The upper extremity of the outer wall 26 is spaced slightly from the upper periphery of the upper intermediate wall portion 12, thus 30 providing an annular air nozzle or discharge opening 35 which is directed toward the inner wall of the jacket 2.

The lower casing 14 is supported within the ash pit 41 by means of a plurality of legs 19 35 each having a slot 29 and a clamping bolt 28 coacting with the slot therein, for permitting adjustment of the effective vertical length of the legs. The lower casing 14 also has an upper flange 31, and the legs 19 are preferably 40 so adjustable that the flange 31 may be brought closely adjacent to the grate supporting flange of the furnace or boiler. The outer wall 26 is moreover preferably so formed that the inner and intermediate walls and the 45 atomizing bulb 4 are freely vertically removable therefrom. The sheet metal air supply duct 15 is in open communication with one side of the casing 14 and penetrates the front closure 21, the joint between the duct 15 and 50 the closure 21 being thoroughly packed in order to prevent leakage of air. The inlet opening of the duct 15 is controllable by means of a flap valve 18 the position of which may be varied by means of a rod or cable 37. The delivery of oil from the reservoir or tank 25 55 through the pipes 16, 6 is controllable by means of a valve 24. It will be obvious that control of the air and oil valves 18, 24 respectively, may be effected either manually or automatically by means of a thermostat, not shown.

When installing the improved oil burner in a furnace or boiler, the lower casing 14 may be first inserted in the ash pit 41 through the 60 front opening in the base section 27, after

which the legs 19 may be adjusted to properly position the flange 31 closely adjacent to the grate supporting flange. The sheet metal air duct 15 and the closure 21 may then be properly positioned and the supply and overflow pipes 16, 17 may be permanently connected to the overflow basin 8 as shown. The attachment of the closure 21 to the base section 27 should be such that no air can enter the furnace except through the inlet opening of 75 the duct 15. After the lower casing 14 has been properly installed, the annular outer wall 26 may be inserted through the fire door 30 and properly arranged upon the lower casing 14. The intermediate and inner walls 80 may then be likewise applied and positioned through the fire door 30, after which the atomizing bulb 4 may be permanently attached to the overflow basin 8 by means of the distributing nozzle 5 and the central feed pipe 85 6. It will thus be noted that the installation of the burner is relatively simple, and that the various elements are also readily removable for inspection and cleaning.

When it is desired to start the improved hydro-carbon burner, a small quantity of highly flammable oil should first be deposited in the overflow basin 8 and ignited. While this oil is burning violently, the valve 24 may be opened to cause oil to flow by gravity from the supply tank 25 through the supply pipes 16, 6 and through the nozzle 5, into the trough or basin 7. The flame produced by ignition of the starting oil in the overflow basin 8, shoots upwardly along the outer surface of the atomizing bulb 4 and of the heating fins 10, and heats the bulb 4 adjacent to the oil filled basin 7 to such an extent that the oil in the basin 7 is vaporized and fills the interior of the bulb 4 with combustible gas. The gas thus produced eventually travels downwardly and through the slots or openings 9 whereupon it is immediately mixed with air entering the chamber 20 through the duct 15 and casing 14. The mixture of air and gas simultaneously advances toward the chamber 38 and is ignited thus serving to automatically maintain the atomizing bulb in heated condition and causing continuous gasification of the oil admitted to the basin 7. The ignited mixture of air and gas is further mixed with an abundant supply of air delivered through the conduits 35, 39 and the combustion of the mixture continues throughout the combustion chamber 3. The flames produced in the initial combustion chamber 38 are forced outwardly by the wall of the bulb 4 and by the plate 34, being delivered against the inner wall of the jacket 3 and thoroughly heat the water in the jacket. The gases of combustion pass upwardly from the combustion chamber 3 through the openings 33, and are eventually discharged up the stack thus automatically producing the draft which is necessary to draw a proper amount of air through 130

the burner to support combustion. By controlling the air and oil valves 18, 24 the amounts of oxidizing agent and fuel admitted to the apparatus may be accurately regulated to produce complete and efficient combustion and to provide only sufficient heat to meet requirements.

It will thus be noted that an extremely simple, compact and efficient hydro-carbon burner is provided, which is entirely automatic in operation and which may be readily installed in and subsequently removed from any standard furnace or boiler. After being properly started the hydro-carbon burner will continue to operate without interruption, the operation being independent of external source of energy such as electricity, water or fuel gas other than that generated in the bulb 4. The burner is obviously devoid of moving parts which might become inoperative, and its operation may be safely effected and maintained by relatively unskilled attendance.

It should be understood that it is not desired to limit the invention to the exact details of construction and operation herein shown and described, for various modifications within the scope of the claims may occur to persons skilled in the art.

It is claimed and desired to secure by Letters Patent:—

1. In an oil burner, a casing forming an imperforate dome having a constricted open lower end, means forming an annular trough exposed to the upper enlarged interior of said dome, means for feeding liquid fuel into said trough, an inner wall forming an annular passage surrounding the lower open end of said casing and directed upwardly toward the outer surface of said dome, an outer wall surrounding said inner wall and forming an annular passage surrounding said casing and having a constriction adjacent to the

upper end of said inner wall, and means for conducting air to the open lower ends of said walls.

2. In an oil burner, a casing forming an imperforate dome having a constricted open lower end, means forming a liquid receptacle below said open end, means forming an annular trough exposed to the upper enlarged interior of said dome, means for feeding liquid fuel into said trough, means operable by liquid flowing from said receptacle for controlling said liquid feeding means, an inner wall forming an annular air passage surrounding the lower open end of said casing and directed upwardly toward the outer surface of said dome, and an outer wall surrounding said inner wall and forming an annular air passage surrounding said casing and having a constriction adjacent to the upper end of said inner wall.

3. In an oil burner, a casing forming an imperforate dome having a constricted open lower end, means forming a liquid receptacle below said open end, means forming an annular trough exposed to the upper enlarged interior of said dome, means for feeding liquid fuel into said trough, means operable by liquid flowing from said receptacle for controlling said liquid feeding means, an inner wall forming an annular air passage surrounding the lower open end of said casing and directed upwardly toward the outer surface of said dome adjacent to said trough, an outer wall surrounding said inner wall and forming an annular air passage surrounding said casing and having a constriction adjacent to the upper end of said inner wall, and controllable means for conducting air to the open lower ends of said walls.

In testimony whereof, the signature of the inventor is affixed hereto.

BRUCE K. INGLIS.
